DEVICE FOR TEACHING MORSE CODE

Victor W. Bolie, Stanford, Calif., assignor to Iowa State College Research Foundation, Inc., Ames, Iowa, a corporation of Iowa

Filed Dec. 11, 1958, Ser. No. 779,659

3 Claims. (Cl. 35—8)

This invention relates to a cryptographic device and method of manufacture and, more particularly, to a device adapted to decode Morse code.

It is an object of this invention to provide a novel cryptographic device—one particularly suited for arranging the code symbols of a Morse code in one portion of the device and thereupon having another portion of the device visually present the alphabet or other language element to which the code symbol pertains. Another object is to provide a method of constructing a decoding device which is easily carried out so that, if desired, the operation can be performed manually. Still another object is to provide a device for cryptographic analysis and a method of fabrication in which the device is a compact and rugged instrument capable of hard usage yet accurate in a decoding operation. Yet another object is to provide a novel cryptographic device and method of fabrication thereof in which relatively few elements are quickly assembled in a procedure that permits of considerable variation so as to provide for the interpretation of a large variety of code symbols. Other specific objects and advantages of the invention will appear as this specification proceeds.

This invention, in an illustrative embodiment, will be explained in connection with the accompanying drawing, in which—

Fig. 1 is a perspective view of a device embodying the teachings of this invention;

Fig. 2 is an exploded perspective view of the device seen in Fig. 1;

Fig. 3 is an enlarged elevational view of various internal elements of the device, showing the arrangement of apertures that aid in achieving the decoding operation; and

Fig. 4 is an enlarged cross-sectional view of the device of Fig. 1, taken along the line 4—4 of Fig. 1.

Referring now to the drawing, the numeral 10 designates generally a device adapted to decode Morse code. The device 10 includes a top plate 11 and a bottom plate 12 secured together by means of bolts 13 (best seen in Fig. 4) in spaced-apart, parallel, aligned relation so as to form a generally hollow frame.

The top plate is equipped with 26 apertures 14, each of which is aligned with a letter of the alphabet 15 provided on the bottom plate 12. This can be quickly appreciated from a consideration of Fig. 2.

Interposed between the top plate 11 and the bottom plate 12 for slidable movement therebetween are four intermediate plates or masking elements 16, again most clearly seen in Fig. 2. These elements 16 are also seen in Fig. 3. Each element 16 is equipped with apertures 17 corresponding in number to the apertures 14 provided in the top plate 11. Each element 16 is also equipped with an extension 18, the extension being in the plane of the plate-like elements 16. The extensions 18 are each equipped with an upstanding handle 19 which protrudes above the top surface of top plate 11 through slots 20. Thus, movement of handle 19 provides for

movement of the associated elements 16. Each extension 18 is also equipped with a dot and a dash symbol spaced apart in the direction of the length of slot 20 so that the dash or dot designated 21 and 22, respectively, in Fig. 3, is selectively brought beneath a window 24 provided in the top plate 11. Intermediate the dot 21 and handle 19, each extension 18 is blank as at 23 in Fig. 3 so that at one position of element 16 no symbol will be viewed through window 24.

In the operation of the device, a given code symbol arrangement of dots and dashes is provided by positioning the various handles 19 so as to disclose the desired dot and dash arrangement in the sequence desired under windows 24. Because of the aperturing arrangement with which each masking element 16 is equipped, only the letter 15 corresponding to the code symbol will be visible. Thus, the person employing the device can sequentially arrange the code symbols to be coded underneath the windows 24 and immediately read the alphabet letter in question.

In the fabrication of the device illustrated, the top plate is equipped with the apertures 14 and four intermediate masking elements 16 are provided. At the outset, these elements are without apertures, so that no letter can be seen through any of the apertures 14. Thereafter, the dot and dash arrangement for a given letter is arranged by moving the handles 19 as needed. For example, relative to the letter "A," the handle 19 for the uppermost element 16 (this element being designated by the numeral 16a) is positioned midway in its associated slot 20a so as to provide a dot in the slot 24a associated therewith. The handle associated with the second from the top plate (this plate being designated 16b) is positioned at the upper extreme of the associated slot 20b so as to position a dash beneath window 24b. The remaining handles corresponding to plates 16c and 16d are positioned at the lowermost position within their associated slot 20 so that neither a dot nor a dash is seen. Thereafter, aligned openings are provided in the four plates to reveal the letter "A" as found on the interior side of the bottom plate 12. This procedure is performed with each of the subsequent letters of the alphabet, so that, in the illustration given, the code arrangement would result in aperturing of the various masking plates 16 in the form shown in Fig. 4.

In Fig. 3, it is seen that the extensions 18 are narrower than the plates 16 and are arranged so that the extensions lie in side-by-side, non-overlapping relation. In this way, a single top plate equipped with four windows 24 is able to disclose the dots and dashes of each one of the elements 16.

Again in Fig. 3, it will be seen that each row of letters 15 on bottom plate 12 is matched by at least two rows of apertures 17 in the plate 16. Exactly two rows of apertures 17 are provided in plate 16a, inasmuch as each letter of the alphabet requires either a dot or a dash in the first position or underneath window 24a.

On the other plates, however, many of the rows of letters (also the rows of apertures 14 in top plate 12) will have three rows associated in the masking plate 16. For example, the upper row of letters in plate 12 includes the letter "E," which is represented in Morse code by a single dot. The corresponding aperture in plate 16b is designated by the numeral 17a and is seen to lie in a row different from the remaining aperture rows 17b and 17c. In element 16b, the apertures 17 will all be arranged in two rows for each row of letters 15 in plate 12 with the exception of the rows containing the letters "E" (as described) and the letter "T" as designated in Fig. 3 by the numeral 17d.

This stems, of course, from the fact that the letter "T" is represented by a single dash.

It is possible to extend the device shown to include other Morse symbols such as the five element symbols for the various numerals 1-0. All that is required is an additional plate 16, which results in an additional window 24, the same procedure being followed for the fabrication of the device. Still further, the code symbols representing various punctuation marks, the punctuation requiring six element symbols, can be conveniently provided through the use of six intermediate plates 16 and six windows 24.

A wide variety of manufacturing procedures can be employed, as well as a wide variety of materials. Preferably, the materials should at least be opaque so that the presence of one plate 16 in covering relation to a reading aperture 14 prevents inadvertent misreading. This can be conveniently provided by making the plates 16 out of metal or an opaque plastic material. The device can be readily fabricated by an individual for his own use merely by following the sequence of operations indicated above, wherein the code elements for a given letter or other language symbol are placed in the proper relation beneath the windows 24 and thereafter the plates beneath the proper apertures 14 drilled. Alternatively, the device can be mass produced through stamping operations wherein the aperture arrangement is implanted on a suitable die. If desired, the alphabet arrangement can be changed materially from the four rows shown on the bottom plate 12. For example, the alphabet letters can be arranged in rows in which the letters having the least number of code elements appear first. Such an arrangement would result in the first row having the letters "I," "A," "M," "N," "F," etc. Such an arrangement might be of additional help to a person learning Morse code through the use of the invention.

While, in the foregoing specification, an embodiment of the invention has been set forth in considerable detail, it will be understood that such details may be varied widely by those skilled in the art without departing from the spirit of my invention.

I claim:

1. In a device for decoding Morse code, a top plate and a bottom plate secured together in spaced-apart, parallel, aligned relation, said top plate being equipped with at least twenty-six apertures, one for each letter of the alphabet, the letters of the alphabet being positioned on the interior of the bottom plate for view through the top plate apertures, at least four masking plates being also equipped with at least twenty-six apertures and movably mounted between said top and bottom plates, the apertures in said masking plates being so arranged that for any given position arrangement thereof only one alphabet letter is visible, each of said masking plates being equipped with an extension carrying handle means extending through a slot in said top plate, the plate extensions lying in side-by-side relation and each carrying a dot and a dash, and a window in said top plate for each

extension, the windows being arranged in a row and each adapted to disclose respective portions of its associated extension bearing no code information, a dot, and a dash.

- 5 2. In a device for decoding Morse code, a top plate and a bottom plate secured together in spaced-apart, parallel, aligned relation, said top plate being equipped with at least twenty-six apertures, one for each letter of the alphabet, the letters of the alphabet being positioned on the interior of the bottom plate for view through the top plate apertures, at least four masking plates movably mounted between said top and bottom plates, each of said masking plates also being equipped with at least twenty-six apertures, the apertures in said 10 masking plates being so arranged that for any given position arrangement thereof only one alphabet letter thereof is visible, each of said masking plates being equipped with an extension, with each extension being free of any over-lapping relation with the other extensions, a portion of each extension projecting beyond said top plate to permit confined slidable movement of the extension relative to the top plate, each extension carrying dot and dash symbols and a blank space, and viewing means on said top plate, said symbols and blank space 15 on said extensions being selectively alignable with said viewing means to permit view of any one alphabet letter for any given position arrangement.
- 15 3. In a device for decoding Morse code, a top plate and a bottom plate secured together in spaced-apart, parallel, aligned relation, said top plate being equipped with at least twenty-six apertures, one for each letter of the alphabet, the letters of the alphabet being positioned on the interior of the bottom plate for view through the top plate apertures, at least four masking 20 plates movably mounted between said top and bottom plates, said masking plates also being equipped with at least twenty-six apertures, the apertures in said masking plates being so arranged that for any given position arrangement thereof only one alphabet letter is visible, each 25 of said masking plates being mounted between said top and bottom plates for confined movement relative to said plates, each of said masking plates being equipped with an extension projecting beyond said top plate to position its associated masking plate in any one of three 30 positions corresponding to a dot, dash, or blank space, and cooperative indicia means on said top plate for positioning said projections in any one of said three positions.
- 35 4. In a device for decoding Morse code, a top plate and a bottom plate secured together in spaced-apart, parallel, aligned relation, said top plate being equipped with at least twenty-six apertures, one for each letter of the alphabet, the letters of the alphabet being positioned on the interior of the bottom plate for view through the top plate apertures, at least four masking 40 plates movably mounted between said top and bottom plates, said masking plates also being equipped with at least twenty-six apertures, the apertures in said masking plates being so arranged that for any given position arrangement thereof only one alphabet letter is visible, each 45 of said masking plates being mounted between said top and bottom plates for confined movement relative to said plates, each of said masking plates being equipped with an extension projecting beyond said top plate to position its associated masking plate in any one of three positions corresponding to a dot, dash, or blank space, and cooperative indicia means on said top plate for positioning said projections in any one of said three positions.
